HARALD SYVERTSEN, OF YORK, PENNSYLVANIA, ASSIGNOR TO S. MORGAN SMITH COMPANY, INC., OF YORK, PENNSYLVANIA, A CORPORATION OF PENNSYLVANIA

PLATE-STEEL SPEED RING FOR HYDRAULIC TURBINES

Application filed September 16, 1927. Serial No. 219,972.

This invention relates to turbine installations and particularly to plate steel speed ring structures and the associated parts which will be varied in construction to adapt the 5 same to various types of installations.

One of the objects of the invention is to make it possible to form speed ring parts of plate sheet steel structural elements, instead of forming them of the usual heavy castings, 10 so as to reduce the cost of manufacture and installation, and eliminate the danger from casting strains and the necessity of making expensive patterns, and at the same time preserve the necessary strength and strain resis- 15 tance of the parts or casing of the turbine wheels or runners.

A further object of the invention is to economically and effectively assemble the plate sheet steel parts in the formation of the im- 20 proved speed ring and to utilize to the best advantage, in the manufacture and assembly of the several parts, plate sheet steel as it comes from the rolling mills in standard plates or forms.

25 It will be understood that the sheet metal speed ring embodying the features of the invention can be used as well with concrete scroll cases as with plate sheet steel cases, or it can be used where especially rigid struc- 30 tures are desired, for open flume or pressure flume hydraulic turbine settings.

The invention consists essentially of the construction and arrangement of the several parts which will be more fully hereinafter 35 described and claimed.

In the drawings:—

Fig. 1 is a transverse vertical section of 40 a hydraulic turbine setting with the scroll casing and draft tube and lower associated structure broken away, illustrating one form of the improved plate sheet steel speed ring installation.

Fig. 2 is an enlarged transverse vertical section of a portion of the installation and 45 particularly showing the form of the speed ring illustrated by Fig. 1, parts of the turbine mechanism shown in Fig. 1 being omitted.

Figs. 3, 4 and 5 are transverse vertical sections of portions of the turbine structure 50 similar to Fig. 2, and particularly showing

modifications in the assembly of the improved plate sheet steel speed ring.

The numeral 5 designates the general structure of the turbine case with which is associated a scroll case 6 which may be formed 55 of plate sheet steel, cast metal or concrete, the specific structural connection of this scroll case being immaterial so far as the effectiveness of structure and function of the improved plate sheet steel speed ring is con- 60 cerned. Within the turbine casing 5 is a runner or wheel A of the Francis type at- 65 tached to the lower end of a shaft 7. With the runner and the improved speed ring a series of wicket gates 8 are associated, as 70 usual, to serve as water inlet controls. It will be obvious that the water inlet controls may be in the form of cylinder gate means. The wicket gates 8, as shown, will be pro- 75 vided with the ordinary or well known oper- 80 ating means 9 to control the operation there- 85 of. The improved plate steel speed ring can also be used with the runner removed and the structure may be used with wicket gate or cylinder gate control cases, as a discharge 90 casing or valve. All of these variations will not in the least affect the features of the in- 95 vention and are obvious changes well known in the art of hydraulic installations of this type. The shaft 7 is ordinarily connected 80 to a generator. The usual draft tube 10 is applied to the present turbine installation and it, together with the structure adjacent thereto, are shown as partially broken away. The draft tube may be of any of the well 85 known types and formed of plate sheet steel, cast metal or concrete.

The features just referred to, except the plate steel speed ring, are well known in the art of turbine installations, and may be 90 varied or modified in accordance with the usual practice in turbine installations.

As shown by Figs. 1 and 2, the speed ring is composed of an upper plate 11 of which the inner periphery is welded, as at 12, to a standard size bar iron 13 circularly bent and terminally welded. The upper ring or plate 11 cooperates with a lower ring 14, and be- 95 tween the upper and lower rings 11 and 14, guide vanes 15 are interposed and connected. 100

The rings 11 and 14 are bent upwardly and downwardly, respectively, near the outer peripheries thereof, as shown, and the guide vanes 15 are preferably curved along a section cut by a plane at right angles to the axis of the turbine, and are formed of steel plates of such thickness as may be required. The guide rings may be shaped as found necessary, and constructed as to strength and durability in accordance with hydraulic conditions or loads to be sustained. The lower ring or plate 14 is supported by a vertical ring 16, a horizontal ring 17, a lower vertical ring 18 and a horizontal supporting flange 19. In connection with the lower structure comprising the rings 14, 16, 17, 18 and flanges 19 there are a number of ribs 20 which are arranged radially to add stiffness and strength to the structure. Similar ribs may also be applied to the top ring 11, as at 21. In cutting the parts from the sheets as they come from the rolling mill in standard plates or forms, the most economical procedure is adapted. For example, the horizontal ring 25 can be cut from the same sheet as the lower ring 14, or, possibly from the same sheet as the upper ring 11. The guide vanes 15 and the ribs 20, as well as the ribs 21, may be cut from the inside of the sheets used for the rings 11 and 14 or the rings 17 and 19. All of the rings, both those vertically and those horizontally disposed, will be welded together as at α to form one solid structure, and Fig. 1 shows the runner with its gate 30 case inside of the speed ring, and also illustrates a part of the sheet steel scroll connected to the speed ring.

In the improved construction the lower structure or element, built up as herein specified, forms an enclosing ring for the bottom band 6^a of the runner, and a removable bottom plate 22 seated on the horizontal ring 17 forms the actual water joint 23 with the runner band, and is secured, as by bolts, to the speed ring. The speed ring can therefore, be anchored or embedded in the concrete, and, when the speed ring is so anchored or embedded, the bottom plate 22, when worn by the scouring action of the water or otherwise damaged, can be removed, and can also be removed when it is desired to take out the runner. The cast metal bottom plate 22 also serves as a lower support for the wicket gates 8 and, since it is made separate, and in view of its capability of easy removal and renewal, is materially advantageous. The metal speed ring is subject to little or no wear, and is adapted to be embedded in the concrete.

Figs. 3, 4 and 5 illustrate modifications of the improved structure, and all embody the upper and lower rings 11 and 14, the stationary guide vanes 15, the cast metal bottom plate 22 and the ribs 20, these similar parts being indicated by like reference characters.

65 In Fig. 3 a circularly bent channel iron 24

is shown in the place of the standard bar iron 13, and such other changes that are necessary in the top structure of the turbine casing are made. For example, the top plate 25, as shown by Fig. 1, would be of slightly different design in order to provide a properly shaped mounting for this different form of speed ring. The lower part of the speed ring in this modified structure is formed by supporting the plate 14 by a vertical ring 70 26 which is, in turn, supported by a circularly bent channel iron 27, and the ring 11 has associated therewith a plate steel sheet scroll 28.

In Fig. 4 the speed ring is shown as associated with a concrete scroll case 29, and the ring formed of standard bar iron 13 shown in Figure 1 is replaced by a circularly-bent angle iron 30. The lower plate or ring 14 is shown as supported by a vertical ring 31, and the latter in turn is shown as supported by a 80 horizontal ring 32 which is welded to and supported by a circularly bent channel iron 33.

In Fig. 5 the speed ring is shown as associated with a cast metal scroll case 34, the upper part of the speed ring being constructed substantially as shown by Figs. 1 and 2, and the lower part of the speed ring having the lower plate or ring 14 supported directly by a circularly bent channel iron 35 and on this is welded, riveted or otherwise fastened a circularly bent angle iron 36 of which the horizontal flange supports the bottom plate 22.

In all the structures disclosed the upper 100 and lower rings 11 and 14 are curved at their outer extremities to provide smooth passages for the water. These passages gradually decrease in area, in the direction of flow, to increase the velocity of the water in efficient 105 manner. The velocity in the plate steel, concrete or cast metal scroll with which the improved plate metal speed ring is associated is lower than the velocity between the guide vanes of the speed ring, and, therefore, to have the least losses in friction and the least disturbance, it is necessary to increase the velocity as gradually and smoothly as possible. The velocity of the water, after passing between the vanes of the speed ring is increased 110 as the water passes between the gates 8 of the turbine. One of the important features of the present improvement is that, since the bottom plate 22, whether it be mounted in concrete or in a metal structure, is formed 115 separately from such structure and, therefore, may be readily removed. This is important in view of the fact that this bottom plate is subjected to excessive wear, whereas the plate metal speed ring is subjected to little 125 or no wear and may be embedded in concrete when such form of installation is adopted. Furthermore, in the improved structure in its various forms, cast or heavy metal parts are replaced by a lighter metallic structure 130

without decreasing the necessary strength and strain resistance. Moreover, the improved metal speed ring is advantageous in that it can be used with a concrete scroll as well as with a plate steel scroll, or it can be used where especially rigid structures are desired.

The bottom plate 22, as shown by Fig. 3, is provided at its outer edge with a depending extension 22^a to accommodate the particular mounting of the channel iron 27, this channel iron replacing the horizontal ring 17, vertical ring 18 and lower horizontal supporting flange 19, shown by Fig. 1. In the modification shown by Fig. 4, the horizontal ring 32 and vertical ring 31 correspond, respectively, to the horizontal ring 17 and vertical ring 31 of Figure 1, and the vertical web of the channel iron 33, which supports the horizontal ring 32, corresponds to the vertical ring 18 of Figure 1. In the modification shown by Fig. 5 the parts 16, 17, 18 and 19 shown in Fig. 1, are replaced, respectively, by the channel iron 35 and the angle iron 36, the latter supporting the bottom plate 22. In all of the structures shown, as heretofore indicated, the bottom plate 22 is removable and the upper and lower rings or plates 11 and 14 of the speed ring are similar in construction and possess the advantages heretofore explained.

What is claimed as new is:—

1. In a turbine installation, the combination with a casing, a runner mounted therein, a scroll and means for controlling the entrance of water to the runner, of upper and lower plates with outwardly curved ends secured to the scroll and having vanes fixed therebetween, a standard metal bar welded to the upper plate, a bottom plate associated with the lower plate, and a supporting structure below the bottom plate and the lower plate of the speed ring.

2. In a turbine installation, the combination with a casing, a runner mounted within the casing, a scroll, and means for controlling the inlet of water to the runner, of a speed ring of plate sheet steel and having upper and lower plates with interposed vanes connected thereto, a circularly bent bar welded to the upper plate, a removable bottom plate under the means for controlling the entrance of water to the runner, the bottom plate being connected to the lower plate of the speed ring, and a supporting structure below the said bottom plate and the lower plate of the speed ring and having angularly disposed components.

3. In a turbine installation of the class specified, the combination with a casing, a runner having a bottom band mounted therein, a scroll and means for controlling the inlet of water to the runner, of a speed ring comprising upper and lower plates with outwardly curved terminals connected to the scroll

and having vanes therebetween, a circularly bent metal band secured to the upper plate, a bottom plate below the said means for controlling the entrance of water to the runner and secured to the lower plate of the speed ring, and a supporting structure below the bottom plate and lower plate of the speed ring and consisting of angularly disposed members, the bottom structure forming an enclosing means for the bottom band of the runner and the bottom plate forming the actual water joint with the said runner band.

4. In a turbine installation of the character specified, the combination with a casing, a runner having a bottom band mounted therein, a scroll, and wicket gates for controlling the inlet of water to the runner, of a speed ring located outside of the wicket gates and including upper and lower plates which have their outer extremities curved and flared and secured to the scroll and vanes therebetween, a circularly bent metal bar to which the inner periphery of the upper plate is secured, a removable bottom plate having its inner periphery adjacent to the runner and forming with the band of the latter the actual water joint and serving to also support the wicket gates, and a supporting structure below the said bottom plate and the lower plate of the speed ring and having members disposed at angles to each other.

5. In a turbine installation of the class specified, the combination with a casing, a runner having a bottom band mounted therein, a scroll, and wicket gates controlling the inlet of water to the runner, of a speed ring formed of plate sheet steel and comprising upper and lower plates with outwardly curved divergent terminals associated with the scroll and vanes therebetween, a circularly bent metal bar secured to the upper plate, a removable bottom plate associated with the lower plate and having its inner periphery adjacent to the bottom band of the runner and forming a lower support for the wicket gates, and a structural plate sheet steel support below the lower plate of the speed ring and said bottom plate consisting of a vertical ring, a horizontal ring, a second vertical ring, and a lower horizontal ring, all connected, the upper and lower plates of the speed ring also having radially arranged ribs connected to the said structure.

In testimony whereof I have hereunto set my hand.

HARALD SYVERTSEN.
